FEED COLLET

Guy Laughlin, Birmingham, Mich.

Application January 16, 1933. Serial No. 652,071

5 Claims. (Cl. 29—62)

This invention relates to feed collets of the type employed in automatic and hand-operated screw machines, bar forming machines and the like.

5 Briefly stated, one of the aims of the invention is to provide a feed collet of the type described in which the pads or work gripping elements are freely interchangeable to allow of the employment of pads of various sizes and configurations, 10 according to the size and cross-sectional formation of the work, of whatever nature it happens to be, all without removing the collet from the machine to which it is attached.

Another aim of the invention is to provide a 15 feed collet of the detachable pad type in which the resiliency of the fingers of the collet is relied upon to hold the pads in place when the chuck is not in actual use.

By way of further brief reference to the mounting of the pads it is pointed out that the longitudinal edge portions of the pads protrude beyond the longitudinal edges of the supporting fingers to define contacting bearing lands or points that are freely grindable to allow the resiliency of the 25 body to bring the pads closer together and thereby compensate for the wear that invariably takes place as an incident to movement of stock through the chuck.

A further aim is to provide a feed chuck of the 30 type described, which is of highly simplified construction, cheap to manufacture, and one which may be employed without departing from established production methods.

Other objects and advantages will be apparent 35 during the course of the following description.

In the accompanying drawing forming a part of this application and in which like numerals are employed to designate like parts throughout the same,

40 Figure 1 is a perspective of the improved feed collet.

Figure 2 is an end view of the collet,

Figure 3 is a fragmentary side elevation of the collet in engagement with a piece of work, a portion 45 of the collet being broken away,

Figure 4 is a vertical transverse sectional view taken on line 4—4 of Figure 3,

Figure 5 is a side elevation of the collet, partly 50 in section, and illustrating the edges of the pads in engagement with each other to hold the pads in place,

Figure 6 is a perspective of a filler embodied in the invention, and

Figure 7 is a side elevation of the collet, the 55 view illustrating the means by which the leaves

of the collet may be separated to remove or attach the filler.

In the drawing, wherein for the purpose of illustration is shown a preferred embodiment of the invention, the numeral 5 generally designates a tubular body, which may be formed from pressed metal, tubing, cast metal or machined from solid stock, having the conventional attaching means 6 in the form of an externally threaded stem. If desired, the attaching means 60 65 may be in the form of an internally threaded stem.

It is clearly shown in Figures 1, 3 and 5 that the tubular body is provided with a plurality of spaced parallel longitudinally extending slots 70 opening out through the forward end of the body and defining transversely curved spring leaves 8. With particular reference to Figure 3 it will be seen that the forward end portions of the leaves 8 are extended inward to define strengthening 75 and retaining shoulders 10 of arcuate form, such shoulders being located in advance of circumferential shoulders 12 formed on the inner sides of the leaves.

The shoulders 10 and 12 define what might be 80 said to be an annular groove receiving the outer portions of a filler embodying a plurality of arcuate pads 14. More specifically, the pads 14 are snugly positioned between the shoulders 10 and 12 and are held against longitudinal shifting 85 thereby. The pads 14 may be constructed from different kinds of material, such as tool steel, cast iron, bronze or chromium plated to meet existing requirements.

It is shown in Figures 1, 5 and 7 that the pads 90 14 are increased in circumferential measurement toward points between the ends thereof and that the longitudinal edge portions of the pads protrude beyond the longitudinal edges of the fingers 95 8 thereby defining opposed lands in the form of 95 substantially equi-lateral triangles, said lands having apexes in engagement with each other to aid in securing the pads in place and being freely grindable to diminish the bore of the body. That is to say, when it is found that wear has enlarged 100 the bore through the filler 14 the edge portions of the pads and more particularly, the high points of said edge portions may be ground an amount sufficient to restore the bore of the filler to its original diameter. In this connection it is noted 105 that the pads and the shell are of dissimilar materials, the pads being of a more readily grindable material.

Of course, the fingers 8 are tempered to press 110 inwardly and in fact, such fingers are shown to

converge toward the forward ends thereof urging the pads 14 in pressure engagement with the work.

It is shown in Figure 1 that when the improved 5 chuck is not actually in engagement with a piece of stock, the inherent resiliency of the fingers holds the pads securely in place and in this connection attention is invited to Figures 3 and 4 in which it is illustrated that a radial pin 16 is carried by 10 one of the leaves 8 and is received in an opening 18 in one of the pads so as to hold the pads against circumferential shifting, it being obvious that since the pads are in edge to edge engagement it is sufficient in small sized collets to employ 15 but a single pin to inhibit such circumferential shifting of the pads. However, in larger sized collets more than one of the radial pins 16 may be employed to hold the pads against circumferential shifting.

20 Should it be desired to remove the pads for the purpose of grinding the contacting edges thereof, or for the substitution of pads of a different size or cross-sectional formation, it is a simple matter to spread the forward end of the shell with the aid 25 of a suitable number of hand tools 20, as shown in Figure 7.

More particularly, the forward portion of each hand tool 20 is provided with an angularly directed bill of a size to fit easily between opposed 30 edges of the fingers 8 so that when the tool is turned, the space between the fingers will be increased allowing the pads to be easily detached. Of course, as a preliminary to mounting the pads of the required character in the shell, the space 35 between the fingers is temporarily increased with the aid of the hand tools 20. If desired, one hand tool may be engaged with each pair of opposed edges of the fingers.

From the foregoing it will be seen that the feed 40 chuck herein disclosed provides a simple means by which the master or shell may be employed in conjunction with interchangeable pads providing a simple means by which the desired bore may be provided or maintained and it is shown in Figure 5 that the ends of the pads are beveled to allow of the free passage of the work, the bevel at the rear ends of the pads meeting the adjacent corner of the internal shoulder to prevent the jamming of the stock at this point.

45 Having thus described the invention, what is claimed is:—

1. In a feed collet, a tubular body having a bore and a plurality of spring fingers provided with spaced internal shoulders, pads between the shoul-

ders and increased in circumferential measurement toward points between the ends thereof and having the longitudinal edge portions thereof protruding beyond the longitudinal edges of the fingers thereby defining opposed lands in the form of substantially equi-lateral triangles, said lands having apexes in engagement with each other to aid in securing the pads in place and being freely grindable to diminish the bore of said body.

80 2. In a feed collet, a tubular body having a bore and a plurality of spring fingers, a filler within said body and having a series of arcuate pads increased in circumferential measurement toward points between the ends thereof and having the longitudinal edge portions thereof protruding beyond the longitudinal edges of the fingers thereby defining opposed lands in the form of substantially equi-lateral triangles, said lands having apexes in engagement with each other to aid in securing the pads in place, and being freely grindable to diminish the bore of said body.

85 3. In a feed collet, a tubular body having a bore and a plurality of spring fingers, pads within the body and increased in circumferential measurement toward points between the ends thereof and having the longitudinal edge portions thereof protruding beyond the longitudinal edges of the fingers thereby defining opposed lands of triangular form, said lands having apexes in engagement with each other to aid in securing the pads in place and being freely grindable to diminish the bore of said body.

90 4. In a feed collet, a tubular body having a bore and a plurality of spring fingers, pads within the body and increased in circumferential measurement toward points between the ends thereof and having the longitudinal edge portions thereof protruding beyond the longitudinal edges of the fingers thereby defining opposed lands of triangular form, said lands having apexes in engagement with each other to aid in securing the pads in place and being freely grindable to diminish the bore of said body.

95 5. In a feed collet, a tubular body having a bore and a plurality of spring fingers, pads within the body and increased in circumferential measurement toward points between the ends thereof and having the longitudinal edge portions thereof protruding beyond the longitudinal edges of the fingers thereby defining protruding lands, said lands having apexes in engagement with each other to aid in securing the pads in place.
